NONSAGGING, OPPOSITELY-SWINGING
HINGE STRUCTUREJames H. Reichart, Muncie, Ind.; Merchants
Trust Co., executor of said James H. Reichart,
deceased

Application February 28, 1946, Serial No. 650,984

2 Claims. (Cl. 16—164)

1

This invention relates to a closure member or door structure which may swing upon either of two parallel axes spaced apart approximately the width of the door accommodating opening and thus swing oppositely.

This invention is directed to a non-sagging door supporting hinge whereby the invention may be used for heavy refrigerator doors, household doors, etc., as well as doors for bathroom and like cabinets.

This invention may be disposed in concealed position when the door or closure is in closed position.

This invention is peculiarly advantageous for refrigerators, etc., which now are provided with left or right hand opening doors and ownership of one type may be most inconvenient to the owner if he moves and the only available space for the refrigerator is such that the other type would be most convenient.

This invention is directed to a hinge structure, the load capacity of which may be increased or decreased with a minimum of parts and change of parts as hereinafter pointed out.

This invention is directed to a self-bracing, oppositely swingable hinge structure, thereby omitting the necessity of closure guides and supports other than the hinge structure or structures if more than one be employed.

This invention, like that disclosed in copending application Serial No. 517,909 filed January 12th, 1944, now Patent No. 2,414,485, dated January 21, 1947, contemplates the inclusion in each hinge structure, which is of dual type, of a number of parallel members, one of which always swings with the door.

This invention is also directed to the channel or equivalent construction of the outer hinge members and the aligned pivots of the hinge members whereby the channel effect eliminates sagging and the pivots also constitute aligned bearings or supports, as well as catches.

The foregoing briefly summarizes the chief objects and features of the invention. Other objects and features will be pointed out more fully hereinafter.

The full nature of the invention will be understood from the accompanying drawings and the following description and claims:

In the drawing, Fig. 1 is a front elevation of a so-called medicine cabinet including the invention, the door thereof being swung to the left upon the left-hand hinge axis and illustrated in perspective.

Fig. 2 is a similar view of the same structure with the door swung to the right.

2

Fig. 3 is an enlarged transverse sectional view taken on line 3—3 of Fig. 1 and in the direction of the arrows.

Fig. 4 is a top plan view of the mounted cabinet with the door thereof in closed position.

Fig. 5 is a front view of a modified form of hinge unit which includes six successively sized channels, same being link connected together and partly opened to the left.

Fig. 6 is a similar view of the same embodiment partly opened to the right.

Fig. 7 is a front view of the said six channel hinge unit and in extended relation prior to collapse into unit formation as shown in Figs. 5 and 6.

Fig. 8 is a top plan view thereof in extended relation.

Fig. 9 is a front elevation of another modified form of the unit utilizing links, outboard bearings and a mounting plate instead of the links and channels illustrated in Figs. 5 to 8 inclusive.

Fig. 10 is a diagrammatic front and end elevation of one form of self-bracing association of a hinge unit.

Fig. 11 is a similar view wherein the parts have a different arrangement.

In Fig. 4 of the drawings, 15 indicates studding to which lathing 16 with plaster 17 is secured. Between a pair of studs is an opening 18 in which

30 is seated a cabinet 19 having a closure 20. The cabinet is flashed as at 21 about the opening and by which same may be suitably secured if desired to said studding, although cabinet side mounting may be utilized if desired. The cabinet flashing and sides may be grooved as at 22 so as to receive and support shelves 23, see Figs. 1 and 2.

The foregoing naturally is generally applicable to refrigerator units of the portable or built-in type, and also applies to conventional doors and enclosing frames. Since the closure 20 herein laps the opening flashing and the container portion, and is spaced outwardly from the wall, no handles, knobs, etc., are provided on the closure which may have a mirror front.

45 At each of the top and bottom of this opening is located a hinge unit, each unit having two parallel pivotal axes spaced apart, upon either of which the closure may be swung. Each unit is of compact character and is dual in nature providing a rigid, sag eliminating arrangement.

The number of elements in each dual, multiple hinge unit may be increased or decreased, as desired, or required, and the element arrangement thereof may be varied as hereinafter pointed out.

55 In Figs. 1 and 2 the top and bottom units are

identical and similarly mounted so a description of one will suffice for both. A pair of angles 30 and 31 are positioned at opposite ends of each unit and are suitably secured as at 32 and 33 respectively to the flashing 21. These members also secure the bridging channel 34 with upper and lower flanges 35 and 36. Note that flashing 21, see Fig. 3, is cut away as at 21a to nest or accommodate the unit.

Herein the angle 30 has a forwardly projecting portion 38 spaced below the channel flange 36. Herein angle 31, see right-hand corners of Fig. 1, has a forwardly projecting portion 39 spaced above the channel flange 35. A channel 37, see Figs. 1 to 3, is suitably secured to the back of closure 20 and has flanges 40 and 41 projecting therefrom. This channel has a length that is approximately equal to the width of the closure.

A bar or strap link 42, see Fig. 1, has one end pivoted at 43 to portion 39. The other end is pivoted at 44 to flange 40. A link 45 immediately below flange 40 is pivoted to flange 35 as at 46, same being aligned with pivot 44. The other end of link 45 is pivoted at 47 to flange 40 of the closure carrying channel 37.

In alignment with pivot 47 is a pivot 48 upon flange 41 by which it is pivoted to one end of link 49. The other end of link 49 is pivoted at 50 to a projecting portion 38 of angle 30. In alignment with pivot 50 the flange 41 of channel 37 is pivoted at 51 to one end of a link 52 that lies immediately beneath flange 36 of channel 34. The other end of this link 52 is pivoted at 53 to said flange 36 in alignment with pivots 47 and 48 when the door is in the closed position shown in Fig. 4.

As shown in Fig. 1 the outer or left end of opened closure 20 in the top hinge unit has two spaced aligned pivots and the right hand end of the box portion has two spaced aligned pivots, while the two adjacent ends have four pivots which are aligned in pairs, the pairs being spaced apart. When the closure is swung oppositely, see Fig. 2, the number of pivots is the same, that is there are again two at the then left end of the container, two at the then open end of the closure and four spaced pivots at the adjacent portions.

Whenever desired there may be frictionally applied to the structure a cover 54 having parallel flanges 55 and 56 at the top and bottom and curved ends 57 and 58. This is pressure applied and frictionally retained within the flashing supported channel or channels.

Reference will now be had to Figs. 5 to 8, inclusive. Herein 60 indicates the largest channel which may have any length and same is provided with apertures 60a at each end and with top and bottom flanges 61. At one end are aligned bearing or contact members 62. At the opposite end at 63 are pivots to which are connected adjacent ends of links 64 in turn pivotally connected at the other ends at 65 to a channel 66 having flanges 67. Note in Figs. 7 and 8 these two channels are oppositely directed.

Herein channel 66 is apertured at 66a adjacent the ends. These apertures need not be of the same spacing as apertures 60a. At the other end of flanges 67 at 68 are pivoted links 69 which at their other ends are pivoted at 70 to channel 71 having flanges 72. Channel 71 faces the same way as channel 60. Channel 71 is apertured at 71a and same registers with apertures 60a when assembled as shown in Figs. 5 and 6.

The other end of channel 71 is pivotally connected at 73 to links 74 in turn pivoted at their

other ends at 75 to channel 76 having flanges 77 and apertured as at 76a, the spacing of which is like that of apertures 66a. Channel 76 faces the same way as channel 66. To flanges 77 at 78 are pivoted links 79.

In succession channel 81, links 84 and channel 86 are similarly connected, see Figs. 7 and 8. Note that each pair of links has the ends adjacent the larger channel pivoted internally to the flanges thereof and the ends adjacent the smaller channel pivoted externally thereto.

Also note alternate channels are similarly faced and adjacent channels are oppositely faced. Also apertures 60a, 71a and 81a register and apertures 66a, 76a and 86a also register. Like contacts 62 at the outer or remote end of channel 60, the channel 86 and flanges 87 thereof at the outer end mount contacts 88.

Referring to Figs. 5 and 6 observe that corresponding pivots or alternate channels are aligned, as it were, and that when the hinge is opened to the right or left the pivots in alignment with the then hinge axis are vertically aligned and contact. When opened one way, see Fig. 5, outermost contacts 62 are aligned and provide predetermined spacing which is effective to prevent axial separation. When opened the other way, see Fig. 6, adjacent or innermost contacts 88 are similarly effective to prevent axial collapse. Thus a rigid hinge arrangement is provided at all times and in all positions of the closure.

One set of channels, all similarly raced, are secured to a frame, for example by screws, etc., applied through the registering apertures. The other set of similarly raced channels is similarly secured to the oppositely swingable closure. Herein but two apertures per channel are illustrated. However, more may be provided when additional attachment is required. The resulting structure is a mutually reinforcing, load dividing, dual action hinge unit or double capacity type. Note that when the closure is in closed position the pivot and contacts, or which there are two, each of the contacts being coincident with a vertical hinge axis, insures that the closure will seat in the frame opening, and that no additional guide or auxiliary supports are required for door guidance in its seating or closing action, or for supporting such a door when in the closed position.

In other words, the hinge unit is of sag preventing character. This is especially noticeable on heavy doors where the top and bottom thereof are each provided with a unit as aforesaid. Whenever desired a mask or shield, such as illustrated in Figs. 1 to 3 and indicated at 54 therein may be utilized with the invention shown in Figs. 5 to 8.

Reference will now be had to Fig. 9 wherein the outboard bearing type illustrated in Figs. 1 to 4 is included. These outboard members are designated as 89 and 90. Two channels 91 and 92 only are shown and these are similarly connected together by links 93. A special mounting plate 94 may be secured to channel 91. A similar plate may be secured to channel 92. The swingable member usually, however, will be secured directly to channel 92 and the support secured to channel 91 in any desired or required manner if the mounting plate or plates be omitted.

Reference will now be had to Figs. 10 and 11 simultaneously, for same are illustrative of two arrangements. Herein the Fig. 10 embodiment is preferred because, as noted in Fig. 10, all the

upper inclined lines are inclined downwardly to the left and all the lower inclined lines are inclined downwardly to the right. This is a compensating or mutually supporting arrangement, that is sag, if any, is of self-cancelling character, whereas in Fig. 11 all lines are inclined downwardly and toward the same side for both upper and lower sets of lines. No further reference hereto is believed necessary since these figures are diagrammatic only and supplied solely to illustrate this sag compensating or cancellation feature.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, as determined by the appended claims.

The invention claimed is:

1. An oppositely acting multiple hinge structure including in combination a plurality of channels, alternate channels facing in the same

direction, and successive channels confronting each other, successive channels having webs of progressively varying width for channel flange interfitting nesting when closed, and a pair of similar length link bars between each successive pair of channels and pivotally connected to the adjacent ends of each.

2. Structure as defined by claim 1 wherein the links are pivotally secured to the flange portions of the channels and interiorly of the larger channel and exteriorly of the smaller channel.

JAMES H. REICHART.
